UNITED STATES PATENT OFFICE

JAMES E. GROSJEAN, OF LIMA, OHIO

DESIGN FOR A SHOE SOLE

Application filed August 14, 1929. Serial No. 32,405. Term of patent 7 years.

To all whom it may concern:

Be it known that I, JAMES E. GROSJEAN, a citizen of the United States, residing at Lima, in the county of Allen, State of Ohio, have invented a new, original, and ornamental Design for a Shoe Sole, of which the following is a specification, reference being had to the accompanying drawing forming a part thereof, in which—

Fig. 1 is a plan view of a shoe sole, showing my new design;

Fig. 2 is a longitudinal cross-sectional view on line 2—2 of Fig. 1; and

Fig. 3 is a cross-sectional view on line 3—3 of Fig. 1.

I claim:

The ornamental design for a shoe sole as shown.

JAMES E. GROSJEAN.
